UNITED STATES PATENT OFFICE.

MANUEL BRETOS Y CLAVERÍA, OF SANTIAGO DE CUBA, CUBA.

FOLDING DOOR AND SHUTTER.

Application filed January 12, 1923. Serial No. 612,347.

To all whom it may concern:

Be it known that I, MANUEL BRETOS Y CLAVERÍA, subject of the King of Spain, residing at Gallo #22, Santiago de Cuba, Republic of Cuba, have invented a new and useful Improvement in Folding Doors and Shutters; and I do hereby declare the following to be a full, clear, and exact description of the same.

10 This invention relates to rolling doors and shutters, and its principal object is to provide a new structure for rolling doors and shutters in which are improved all the details of construction, which, up to the present have been imperfect and have caused poor functioning.

The invention provides, generally, improvements in brackets and guides of rolling doors, in locks for the doors, in means 20 which permit better adjustment of the component parts of the door, and in other details of importance in the structure of doors and shutters.

Further advantages, and other pertinent 25 considerations, will be deduced in the course of the description more especially by those expert in the art to which the invention belongs, and with the aid of the figures of the accompanying drawings in which like characters of reference designate like parts, and wherein,

Fig. 1 is a front elevation of a door and shutter, the object of the present invention,

Fig. 2 is a rear elevation of the door and shutter,

Fig. 3 is a partial vertical section, in detail, on an enlarged scale, on line 3—3 of Fig. 2,

Fig. 4 is a partial plan top view, on an 40 enlarged scale, of the illustrated detail of Fig. 3,

Fig. 5 is a front elevation, in detail, on an enlarged scale, of means used for rolling the door and shutter,

Fig. 6 is an end elevation of Fig. 5,

Fig. 7 is a partial elevation, in detail, on an enlarged scale, and with parts in section, of the shutter which forms part of this invention,

Fig. 8 is a vertical section on line 8—8 of Fig. 6,

Fig. 9 is a vertical section, in detail, on line 9—9 of Fig. 5,

Fig. 10 is vertical section, in detail, on line 10—10 of Fig. 5,

Fig. 11 is a vertical section, in detail, on

line 11—11 of Fig. 5, and including couplings for the rolling of the door and shutter,

Figs. 12, 13, 14 and 15 shown in perspective different details of means for rolling the door and shutter, and are respectively, a spring washer, a packing, a spacer, and a drum axle,

Fig. 16 is a view of a coupling for the 65 rolling means of the shutter and door,

Fig. 17 is a detail, in section, on an enlarged scale, of a side of the door and anti-friction means for the same,

Fig. 18 is a lateral view of Fig. 17, parts 70 being broken away,

Figs. 19, 20 and 21, are perspective views, showing in detail, different types of anti-friction elements, used with the door and shutter,

Figs. 22 and 24, show in perspective, details of guide rails,

Fig. 23 shows, in perspective, a rail connecting means,

Fig. 25 shows, in perspective, connected 80 rails,

Fig. 26 shows, in perspective, a bolt used in the connector of Fig. 23,

Figs. 27 and 28, show, in perspective, alternative connecting means, for attaching 85 the guide rails to a door opening,

Figs. 29, 30, and 31 show, in perspective, alternative connecting means, to be used with those of Figs. 27 and 28,

Fig. 32 is a partial vertical section, in detail, on line 32—32 of Fig. 7,

Fig. 33 shows a different operative position, in section, of the parts shown in Fig. 32,

Fig. 34 is a partial vertical section, in detail, on line 34—34 of Fig. 7,

Fig. 35 is a partial vertical section, on line 35—35 of Fig. 7,

Figs. 36 and 37 are perspective details, respectively, of a spring, and a handle used 100 on the shutter, and

Figs. 38 and 39 are in detail, different perspective views of links which join together plates that form the articulated roll of the door and shutter.

In Figs. 1 and 2 is shown a rolling door made of corrugated plates 1 and slidable between vertical guide rails 2. The door is provided with a shutter 3, of a kind in which the shutter members hang on metallic ribbons 4, to cover an opening 5 in the door 1 and are slidable between recessed guides 6,

which form the sides of the opening, which guides are connected with vertical bars 7 by means 8 all constituting with horizontal guide bars 9, an articulated system that does 5 not form part of this invention and is therefore not described in more detail.

The guide rails 2 terminate at the top, as illustrated in Fig. 3, in detail, in plates 10 with their rear edges rounded and their 10 front edges straight. Each plate has a peripheral border or flange 10' terminating at an extension 10'' of the face of the plate, and which extension is closed by a small plate 11, of polygonal shape and of a width the 15 same as the border or flange 10'. It is held in position by a screw 12 and a screw 13, to which latter a nut 13' is screwed. The opposite end of screw 13 projects along the plate and has attached a folded metallic 20 plate 14 shaped to follow the outline of the border 10' and fastened by screws 14' to a horizontal flange 15 that projects across the top front part of each plate 10, the object of this plate being later explained. In the 25 straight front part of each plate 10, are two section members 16, having the shape of an inverted U. Within members 16 are fixed corrugated plates 18, for covering the upper part of the door, the lower edge of the plate 30 being supported by small support blocks 19, lodged in recesses 19', in the lower parts of members 16, and held by bolts 20, passing through holes in the inner faces of the front flange 10' of plates 10, and projecting 35 beyond the bracket blocks and into recesses 19'' in line with the grooves 19', and attaching nuts thereto which secure perfect attachment of the parts, and make it impossible to remove, from the outside, the corrugated 40 plate 18.

The connection of the plates 10 to the door opening, is obtained by means of connection arms as illustrated in Fig. 27, whereby the door remains outside of the plane of 45 the door opening. This connection arm consists of a small plate in the shape of a T, with its head and stem positioned in different planes by bending the stem at its point of connection to the head. In the head are 50 horizontal slots 21', and in its stem is a hole 21''. The stem is inserted at the back of an aperture 22, in the front top part of each plate 10, and through hole 21'', receives a bolt 23 that holds it to the bracket plate 10. 55 The position of the bracket plates 10 is then adjustable by means of screws in the slots 21' in the head of connection arms 21, which are fixed to the sides of the door opening.

If it is desired to position the roll formed 60 by the door, in the plane of the door opening, the type of connection arm illustrated in Fig. 28 is used, which same consists of a small plate 24 in the form of a T, but folded at an angle at the union point of its branches. 65 In its head are slots 24', and in its stem a

slot 24'', the stem passing through the aperture 22, to be held by screws to the plate 10.

Between the plates 10 is mounted, in brackets 26, horizontal axle 25 the brackets 26 being secured to the inner middle parts 70 of plates 10, by screws 25', and provided with notches 28', whereby to adjust between them, the seat 25'' of the brackets 26, the ends of the axle 25 being pressed therebetween by tension bolts 27 provided with nuts 29. 75

On the axle 25 is mounted devices for rolling the door 1 and the shutter 3. The door 1 is rolled around two drum rollers loosely mounted in hubs 31, at the ends of axle 25. These hubs are detailed in Fig. 15, 80 having at their ends, longitudinal grooves 31', and at their centers an ear 31'' with a horizontal opening 31''. The hubs are fixed to the axle 25 by means of half collars 32, fixed at each of their ends surrounding the axle 25, and fastened together by bolts 33. Each is provided with a tooth 32', to enter into one of the grooves 31' of hub 31. The roller drums of the door each contain a cylindrical box 34, with a central opening 34', to loosely receive a hub 31, ear 31'' being fixed in the interior of the box. On said boxes around the openings 34', and leaving an annular flange 34'', around the same, are cylindrical open ended extensions 35, in the edges of which are longitudinal grooves 35'. Inside of each extension 35 is a washer 36 of fibrous material which replaces the ball bearings formerly used, which washer is pressed against the annular flange 34'', by a spring washer 37. 90

The boxes 34, contain leaf springs 38, rolled in spiral form, (Fig. 10) each inner end being fixed to a horizontal pin 39 passing through the side walls of the boxes. 105

At the rear of the boxes 34, are fastened, by means of pin bolts 41', clasps 41, formed of a plate curved to follow the outline of the box 34 toward the front, and having its free end bent rearwardly in the form of a claw, to receive the top edge of the door. This top edge is composed of a narrow plate 42, running the entire width of the door and having its lower edge 42', formed to engage the top edge of the corrugated plate 1, that constitutes the door, and its upper edge doubles over to engage the claw. 110

Between the roller drums receiving the body of the door, and on the axle 25, are two roller drums of lesser diameter for rolling the shutter. 115

These drums consists of a hub 43, of the same form as the hub 31, which is also held to the axle by means of collars 43'. The drum includes a cylindrical box 44, which contains a leaf spring 45, and has, around a central opening receiving hub 43, cylindrical extensions 46 and 47, with open extremities having longitudinal grooves 46' and 47', which grooves receive a tooth of a collar 43'. 120

In these extensions are fibre washers 48, and spring washers 49, similar to washers 36 and 37.

Around the inner extension 47, is formed a second cylindrical extension 50, which leaves an annular space 50', and is provided with vertical grooves 50'', its sides being prolonged beyond the sides of the extension 47. Between the corresponding extensions 50 of the inner roller drums is mounted on the axle 25, a large hub or sleeve 51, which terminates in small plates 51' from each of which project two surface coupling cylinders 51'', having longitudinal grooves 51''' in them to match grooves 50'' of the extensions 50, when placed in position telescopically, the members 51'' admitting through the coinciding grooves 50'' and 51''. The screws 52, which adjustably connect member 51 with the inner drums, and permit varying the drum positions according to the width of the shutter.

In the extensions 47, are openings 47'', in the form of crosses in which are engaged the ends of ribbons 4 that suspend the shutter 3, said ribbons being in frictional contact with two plates or brakes 54 provided at their ends with holes 54', through which holes and holes in the plate 42, screws 55 are secured by which means the tension of the brake is graduated. The lower end of 54 is fixed to a lever 56, positioned horizontally between clasps 57 on the rear top part of the door.

When it is desired to make any repairs to the door, or to mount or dismount it, the door being unrolled, the roller drums of the door 1 and of the shutter 3, can be made stationary by means of keys of the form illustrated in Fig. 16. They are each constituted by a half collar 58, provided on its top face, and near its ends, and on its inner face, and centrally, with teeth 58', the lower tooth fitting into the groove 31' of the hubs 31, or in the grooves of the hubs 43, as the case may be, and the upper teeth fitting into the grooves 35' of the extensions 35 of the roller drums of the door, or into the grooves 46' and 47' of the extensions 46 and 47, of the roller drums of the shutter, all the parts thus being held by fixing them on the axle 25.

The rolling device is hidden by a cover 59, of cylindrical form, whose ends are fixed in recesses formed between the rims 10' of the plates 10, and ribs 60 on the bracket inner faces, which ribs are prolongations of the flanges 15, and run parallel to the rims 10', terminating near the part 10''.

The lateral rail guides for the door, are held by means of brackets such as illustrated in Fig. 29 and each includes a plate 61, of angular shape, having wings, in one of which are horizontal slots 61', and in the opposite of which are vertical slots 61'', said wings being joined together by lateral integral extensions 61''' which are prolonged beyond

the wing of the plate that contains the slots 61'.

Each bracket including plate 61 rests with its projections 61''', against the inner side of each guide rail 2, and is there fixed by means of screws 62, of the kind shown in Fig. 26 passing through slots 61''. The screw has a head in the form of a truncated pyramid of rectangular base, and such screws are preferably used to secure the various parts of this construction of door and shutter. In use, the head of the screw rests in depressions in the inner face of the inner side of the rail 2, and projects through the grooves 61', of the plate 61, and receives a nut 62', thus drawing the extensions 61''' tightly into place.

In case it is not desired that the door remain in a vertical plane on being unrolled, but that, at a given height, it deviate backward, in order to allow extra space, the guide rails 2 are cut off at the point chosen, and a switch branch 64, 64', of recessed section of the same width as the rails 2, and in line therewith, is connected to the cut off end. 90 The switch branches can be arranged in any desired direction.

The butting rail joints have matching recesses 64'' (Figs. 22 and 24) connected by means of a joint 66, (Fig. 23) consisting of a plate, folded in the form of a U and with its edges folded inwardly and presenting on one of its sides, openings 65', countersunk in the inner face of the plate. These plates are positioned with their folded edges 100 doubled toward the inside to complete the edges of the rails where interrupted by the recesses 64'', there having first been passed through the openings 65', from inside to outside, screws 62 whose heads lodge in the 105 countersunk portions of openings 65'. The screw ends receive the connection plates 61, which secure the rails 2 to the sides of the door space.

The plates 61 can be replaced by arms 67 110 and 68, such as illustrated in Figs. 30 and 31 depending on whether the door is to be without the plane of the door space, or in such plane.

As may be easily understood, the connecting elements for the supplementary rail, can be easily removed whenever desired, and replaced by sections of straight rails connected to the cut ends of rails 2.

As said before, the shutter 3 is suspended by ribbons 4, and is provided with guide rails 6, and means for connecting the same, to form the frame for the shutter. For the top edge of space 5, to be covered by shutter 3, is a lintel formed of an inverted U plate 125 69, fastened between plates 70 and 71 secured along the width of the shutter, to the faces of the corrugated sheet, forming the door.

In the lintel is lodged the top end of a 130

bar 7, that is connected to the sides 6, of the shutter, as illustrated in Figs. 7 and 34.

The shutter is made of beaded plates, joined together, and the lowermost plate, designated as 72, has a folded edge 72', cut at the center, 72'', to receive a short axle 73. To axle 73 is fixed a piece, illustrated in Fig. 37, composed of a plate in the form of a pedal 74, having at the back, an ear 74' in the form of a handle and connected at a very obtuse angle, with the pedal 74 by a piece having an opening through which runs the axle 73, whose ends lodge in the cut ends of the bead 72'. A leaf spring 75, (Fig. 36) fixed by a rivet to the plate 72, rests with its free end across the handle 74', to hold it in desired normal position.

At the lower edge of opening 5, at the threshold 76, is a narrow plate 77 running the whole width of the shutter and having beaded edges, and admitting through its outer edge a pivot 78, which permits the plate to rotate toward the inside or to remain in an extended horizontal position (Fig. 35) when the shutter is closed, and thus prevent any crevice between the lower edge of the shutter, and the threshold 76. The plate 77, upon the door being rolled up, becomes suspended, as seen in the dotted line (Fig. 35).

The door, as well as the shutter, can be made of corrugated metal sheet, or of beaded sheet joined together. In the case illustrated, the door is made of corrugated metal sheet 1, and the shutter is made of hinged plates with joints reenforced by links 79, detailed in Figs. 38 and 39, each having its lateral sides convex on the exterior and concave on the interior, to aid in rolling, the ends being rounded and with pierced opening 79', and at the middle part of its exterior face, a projection 79''.

These links are superposed laterally at the heads of the articulated plates, their openings 79' coinciding with the end openings of the beads of the joints, and connected together by metallic clamps 80, placed between each two, and fixed to the inner faces of the articulated plates.

The plate 72, is reinforced by a clamp, such as illustrated in Fig. 21, consisting of a small plate 81, reduced laterally to leave a part enlarged, to the extremity of which is fixed a bracket 83' carrying a pulley 83 loosely rotatable therein, the bracket having an extension 82 provided with a tongue 83'' directed in the same direction as the body 81, and lodgable in the bead 72', of plate 72 of the shutter, the plate 81 being fixed to the inner face of plate 72, by means of rivets 84.

In the sides of the door, as well as those of the shutter, antifriction means are provided, in order to obtain smooth sliding in the movement along the guide rails 2 and 6,

whereby the least pressure is sufficient to operate the door and shutter thus provided.

Such means is illustrated in Figs. 17, 18, 19 and 20. In Fig. 19, is a small plate 85, reduced laterally to form an opening having at its end a bracket 86, with a pulley wheel 87, mounted loosely therein, and in the same plane as the body 85.

In Fig. 20 is represented a bracket plate 88, having at its end, a loosely mounted pulley 89, placed in a plane normal to the body 88. The plates 85 and 88 are alternately secured between the corrugations of plate 1 at the lateral edges, and in frictional contact with the rails 2, thus reducing friction and preventing lateral movements and shaking of the door, which would interfere with its raising and lowering.

I also provide means for closing the door which effectually prevents the door and shutter from being opened by unauthorized persons, and consisting of horizontal latches 90, in bearings 90', secured to the rear face of the door, and adapted to its corrugations, the latches being adjustable in sockets 91, in the lateral guides 2, of the door. I also provide lock means 93, which hold the shutter firmly in its closed position.

The lock means 93 consists, (Fig. 7) of an ordinary lock member 94, mounted either on the shutter, or, if the door has no shutter, at the center of the door and at a convenient height. The mechanism of this lock on being operated by a special key, projects bars 95 outwardly and with them, pins 96, guided between members 97, fixed on the inner face of the shutter or door. These pins engage in sockets 98 in the guide rails 6 or 2.

The advantages gained in this manner, are evident, since this lock can be used for a door of any width, without anything further than disconnecting the pins 96 and replacing them by others of the necessary length. For example, although the lock is shown applied to a shutter used in a folding door, this lock could be equally well used in a door having no shutter, by using pins 96 of sufficient length, and sockets in the door guide rails.

The operation of the door and shutter, is as follows:

Assuming the door 1, rolled around the roller drums 34, and the shutter 3 rolled around the drums 44, without any extra thickness resulting due to the lock means 93, which has one of its sections, due to the clearance given by the hub 51, between the small plates 51'. In this position, by means of a bar provided with a hook at its end one of the bolts in the lower edge of the door is engaged and pulled downwardly whereupon the door slides smoothly down between the rails 2, without necessitating any great force, due to the antifriction pulleys

87 and 89 with which the sides are provided. The door once unrolled, and the latches 90 closed, the rails 6 of the shutter 3 are fixed, by first introducing the upper ends of connection bars 7 in the recessed lintel 69 of the frame, and then connecting bars 7 and rails 6, by members 8. A downward pull on the shutter by means of engaging a hook in the handle 74', runs the shutter down between the rails 6.

10 The plate 77, which is in a vertical position, rotates inwardly on the axle 78, and the clutch and pedal 74, 74'', rotate around pivot 73, against the tension of spring 75, so as to assume the position illustrated in Fig. 32. It is then simple to push the latch downward, resting one foot on the pedal 74, and provide a perfect closure on the plate 77.

20 Maintaining the pedal 74 in the horizontal position, serves as a stop against the top post of the shutter, only when the shutter is opened.

If the supplementary rails 65, be used, 25 (Fig. 3) it is sufficient to guide the door between the same on reaching the proper point.

To roll up the door, the shutter 3 is rolled up, by first rotating the pedal and handle 30 74-74', until in the position shown in Fig. 33, which rotates the plate 77, to the position illustrated by dotted lines, in Fig. 35, and then giving the shutter an upward impulse by means of the bar previously mentioned, or similar means.

The plates 54, against which the links 79 rub lessen the speed of the rolling at the end, thus preventing prejudicial shocks to the door.

40 The lateral rails 6 of the shutter, and the connection bars 7, are then folded onto the bottom post of the door, the latches 90 are released, and the door is pushed upward, it being observed that although the motion is vigorous, the last part of the rolling is slow and smooth due to the friction exercised on the door by the brake plates 14, inside of the plates 10.

The closing plate 11, can be dismounted 50 by removing the screws 12, and nuts 13', to facilitate repairs to the door. This is done by first rolling up the door and taking it out through the hole in the bracket normally closed by plate 11.

55 It is evident that within the principles of construction shown, distinct changes can be made without departing from the principles of the invention.

I now claim:

60 1. An apertured door, means for rolling the door, a rolling shutter for covering the door aperture, means for rolling the shutter, the shutter being hung from the top of the door, said shutter being on the inner face of the door, in combination with two brack-

ets, adjusting means for the brackets, and friction brakes in the brackets for retarding speed of rolling of the door and the shutter.

2. In a door opening, lateral guides at 70 the sides of the opening, brackets connected to the upper ends of the guides, comprising plates widened at the back and presenting a straight front, a guide at the front of each bracket, a plate in the guides and covering 75 the upper part of the door opening, demountable blocks in the guides for supporting the plate, connecting arms for adjustably attaching the brackets in the door opening, a curved sheet between the brackets, a screw 80 controlling the position of the sheet, an axle mounted in the brackets, door rolling means on the axle, means for locking the rolling means and axle together, a rolling door connected to the door rolling means, and a 85 cover connected to the brackets and shielding the door rolling means.

3. A rolling door guide, comprising, vertical, parallel, spaced spindles, a substantially inverted Y-shaped guide connected by 90 its stem to each of the vertical guides, and extension guides connected to the arms of the Y guide, whereby to form a main guide, and a switch guide for a folding door.

4. A rolling door guide, comprising, a 95 main guide and a switch guide connected to the main guide, and adjustable slot and screw connecting means for attaching the door guide to a door way.

5. A rolling door and shutter comprising, 100 lateral guide rails, a rolling door within the rails, brackets surmounting the guide rails, a horizontal axle mounted in the brackets, two roller drums mounted toward the ends 105 of the axle for rolling the door, each roller drum including, a hub, a cylindrical box on the hub and having lateral cylindrical extension around the hub, a fiber washer and a spring washer in each extension, a spiral spring inside the box having one end connected to the hub and the other end to the box, collars holding the hub rigid with the axle, connecting means on the exterior of the box for fastening the door thereto, and key 110 means for rigidly interconnecting the box 115 and its hub.

6. A rolling door and shutter according 120 to claim 5, shutter roller drums mounted on said axle between said roller drums, and constructed similarly to said roller drums, an adjustable hub spacer between the shutter roller drums, an aperture in said door, a shutter for covering the aperture, metal strips suspending the shutter from the top of the door and connected to the shutter roller drums, and friction plates bearing against the strips and acting as brakes thereon.

7. In rolling doors and shutters, brackets 130 for holding door and shutter rolling means,

- each bracket comprising a plate having a straight front part, and a widened, rounded back part, a peripheral flange on the plate discontinued at the lower rear portion, a
5 removable flange attached to the plate where the peripheral flange discontinues, a screw in the removable flange, a nut holding the screw to the flange, and a flexible sheet, positioned between the brackets and adjustable
10 by means of the flange screws to act as a friction brake for a rolling door.
8. A guide according to claim 3, each rail connection comprising, notched rail ends, a bent U-shaped clamp placed around the
15 butting rail ends and filling the notched portions, and screws connecting the rail ends and clamp, and having their heads positioned inwardly.
9. In rolling doors and shutters, a clamp
20 piece for the points of major resistance of a door and shutter, comprising, a plate fixed
near the borders of a door and a shutter, a bracket and pulley wheel on the plate, an extension on the plate, and an ear on the
25 extension.
10. An apertured door, a pivoted plate at the base of the aperture rotatable to a horizontal or vertical position, a shutter positioned over the aperture, a handle pivoted to the lower edge of the shutter, and a holding spring fixed to the shutter and bearing against the handle.
11. A rolling door and shutter, means for locking the door and shutter, including, pins mounted horizontally at the sides of the
30 door and sockets secured on the sides of the door, a lock having two pins mounted on the shutter and sockets at the sides of the shutter to receive the pins.

In testimony whereof, I have signed my name to this specification.

MANUEL BRETOS y CLAVERÍA.
